ISAIAH N. ZELLER, OF NEW YORK, N. Y., ASSIGNOR TO AMERICAN SAFETY RAZOR CORPORATION, OF BROOKLYN, NEW YORK, A CORPORATION OF VIRGINIA

SAFETY RAZOR

Application filed December 23, 1927. Serial No. 242,061.

My present invention relates generally to razors and to blades therefor, and more particularly to the type of razor designed for employment with wafer type blades.

One object of the present invention is to provide an arrangement wherein a selected blade may be associated with the holder in a manner which will always position the blade in the proper predetermined relationship with respect to the guard.

Although I have herein illustrated and shall hereinafter specifically describe a device employed with a double-edged blade, nevertheless it will be understood that as to certain phases of my invention, a single-edged blade of a similar character may be employed with equal facility and efficiency.

It is a well-recognized fact that any deviation from the proper predetermined positional relationship of a cutting edge with the guard of a razor holder will result in inefficient shaving. Obviously, therefore, there is a decided advantage in the type of razor exemplified by the "Eveready" and the "Gem" wherein blade stops are associated with the guard edge in a predetermined manner so that the cutting edge, when brought to bear against these stops, will be properly positioned along the theoretical line of maximum shaving efficiency.

Where double-edged blades are employed, and the feasibility of advancing the cutting edge by pressing upon the rear or opposite edge of the blade is lessened, because of the adverse affect upon the inoperative cutting edge, the proper positioning of the blade presents different problems. In the type wherein the positioning is effected by an engagement between pins upon the razor saddle or blade seat on the one hand, and complementary openings or holes through the blade on the other hand, the possibility is greatly increased of having certain blades position themselves properly and other blades improperly. For example, the openings may not be punched through the blade in a strictly accurate manner, and accordingly, one or both of the cutting edges will not assume the proper position upon the blade seat when the pins of the blade seat are passed through these

holes. Or, even assuming that the holes through the blade are properly located, the processing of the blade edges to provide cutting edges thereof may give rise to irregularities and non-uniformity resulting in the same defective positioning.

An important object of the present invention is to provide a razor holder, and a blade for use therewith, wherein certain of the advantageous characteristics of the double-edged type of blade and holder are retained, while certain of the disadvantageous characteristics exemplified above are obviated; also, wherein certain of the advantageous characteristics of the single-edged type, such as uniformly proper positioning, are retained, while the disadvantageous characteristics, such as pressing directly against the rear edge of the blade, are rendered absent.

While the razor holder and the razor blade herein to be fully illustrated and described each presents certain inherent advantages of its own, yet the efficiency of the razor device as a whole will be at its maximum when a blade of the character illustrated and described is employed with a holder of the character illustrated and described. It is accordingly an object of the present invention to construct the razor holder in such a manner that only that type of blade may be used therewith which is herein disclosed and which results in said maximum efficiency.

Other objects of my invention lie in providing a device wherein the positioning of the blade is effected by means of front blade stops of a particular character, the arrangement being such that the effective length of the operative cutting edge is not materially reduced; in providing means for assuring uniformly proper positioning of a selected blade, whether single or double-edged; in providing an arrangement for preventing the use with a particular type of holder of any blade other than that intended therefor and capable of achieving maximum efficiency when used therewith; and in providing generally a new and improved razor holder, and a new and improved blade for employment therewith.

One of the features of my invention lies in

providing a wafer-type blade having beveled side edges, and a razor holder provided with blade stops adapted to cooperate with said beveled side edges for properly positioning the operative edge over the guard edge. More particularly, it is a feature of my invention to provide beveled blade stops in predetermined association with the guard edge for receiving the beveled side edges of the blade in wedged relationship therebetween.

Another feature of my invention lies in providing a blade of the foregoing character which is symmetrical about an axis parallel to its front and rear edges, thereby rendering the blade reversible; and in providing a holder so designed as to receive a blade in proper predetermined relationship, resulting in maximum efficiency, in either normal or reversed position.

More particularly, it is a feature of my invention to provide a razor holder for use with a double-edged wafer-type blade, symmetrical about an axis parallel to the cutting edges, wherein blade stops associated with the guard edge are designed to cooperate with the beveled side edges adjacent to the selected operative cutting edge, and wherein blade-advancing members are designed to cooperate with the beveled side edges momentarily positioned toward the rear, i. e., adjacent to the momentarily inoperative cutting edge.

In the embodiment of my invention herein illustrated and described, I disclose an arrangement of a holder wherein the blade-advancing means are associated with the blade seat itself. The holder is of such a character, and the stops and blade-engaging members are so constructed and arranged that blades of the double edge type can be associated therewith without in any way adversely affecting the functioning either of the razor or of the blade. The disclosure herein is therefore of a double edged blade although, as will be understood, it is not necessary that both edges of the blade be sharpened.

For the attainment of the foregoing objects and such other objects as may hereinafter appear or be pointed out, I have constructed a device embodying the features of my invention and illustrated in the accompanying drawing in which—

Fig. 1 is an elevational view of a holder having a double-edged blade associated therewith in completely assembled relationship and ready for use;

Fig. 2 is a view similar to Figure 1, a portion thereof being shown in cross-section, and the blade seat being shown in an adjusted position;

Fig. 3 is a plan view of the blade seat of Figure 1, a portion of the blade being broken away to disclose the seat underneath; and

Fig. 4 is a fragmentary cross-sectional view

taken substantially along the line 4—4 of Figure 3.

In the drawing, I have shown a device embodying a handle 10, the upper portion of which is externally threaded as at 11 and terminates in a conical end 12 having a rounded apex. The threaded portion 11 is designed to engage within an internally threaded sleeve 13 formed upon one part 14 of a sectional blade seat. The complementary part 15 of the blade seat is pivotally associated with the part or section 14 as by means of a hinge arrangement 16 extending across the entire composite seat and substantially overlying the axis of the handle 10.

Before describing in detail the features of the blade seat and the blade to be accommodated thereby, I will explain that the sections 14 and 15 are arranged to be mutually adjustable from the normal blade-accommodating position of Figure 1 to the adjusted or angular position of Figure 2. In other words, the blade seat section 15 is movable into and out of the plane of the composite seat, the purpose of this movability being explained hereinafter.

To permit of the foregoing adjustment, the sleeve 13 is provided with an opening 17 in one side of the upper portion thereof so that when the handle 10 is screwed upwardly, the end 12 will become exposed in said opening. Along the middle of the section 15, and perpendicular to the hinge axis 16 is a depending rib or cam follower 18 having a contour similar to the letter V with the apex of the V rounded and one of the arms of the V considerably shorter than the other. More particularly, upon referring to Figure 1, it will be noted that the surface 19, constituting one arm of the V, extends downwardly from a point adjacent to the hinge axis 16; this surface then curves back upon itself to form a rounded V apex 20, and it continues then along a gradually sloping surface 21 toward the outer edge of the section 15.

When the holder is in normal position as shown in Figure 1, the surface of the conical end 12 engages with the rounded apex 20 and retains the seat section 15 in its normal position, in the plane of the composite seat. When the handle 10 is unscrewed, the head 12 will be lowered into the position of Figure 2; the section 15 may then be swung downwardly into the position of Figure 2, and it will be noted that the apex 20 will ride over the rounded apex of the end 12. In the position of Figure 2, a screwing up of the handle 10 will cause the apex of the end 12 to bear against the surface 21 initiating the upward movement of the section 15; presently the apex 20 will ride over the apex of the end 12, and thereafter the latter will bear against this apex and force the seat section into the position of Figure 1.

Referring now to Figures 3 and 4, it will be observed that I have shown a double-edged blade 22 having a cutting edge 23 and an opposite cutting edge 24, the side edges of the blade being beveled so as to converge towards each cutting edge. More particularly, it will be noted that a set of beveled side portions 25 converge toward the cutting edge 23, whereas a set of beveled side portions 26 converge toward the cutting edge 24. The blade shown is therefore substantially hexagonal, although it may with equal facility be made octagonal, if desired, the extra two edges of the octagon being arranged at the junction of the side portions 25 and 26. It will further be noted that the blade illustrated is symmetric about an axis parallel to the cutting edges 23 and 24. This symmetry is not necessarily essential, however, for the reason that the blade need not be reversed in order to render both of its cutting edges operative.

The seat section 14 is provided with a guard edge 27 underlying the cutting edge 23, and the seat section 15 is provided with a guard edge 27' underlying the cutting edge 24. On opposite sides of the guard 27, I provide upstanding blade-engaging flanges 28 which converge toward the edge 27 so as to receive the converging sides 25 of the blade 22 therebetween in wedged relationship. In the form illustrated the flanges 28 are doubled back upon themselves to provide channels, whereby the blade is insertable edgewise thereunder and therebetween. The flanges 28 are so constructed and arranged as to serve as front blade stops of the character typical of the so-called "Ever-ready" type of razor; but it will be noted that instead of engaging opposite portions of the front cutting edge, they engage the converging sides adjacent to the cutting edge. One of the functions of the flanges 28 is to assure the proper positioning of the cutting edge 23 with respect to the guard 27. In other words, if the proper blade is inserted between the flanges 28 and forced into wedged relationship therebetween, the cutting edge 23 will automatically assume the proper predetermined position over the guard 27 which results in maximum shaving efficiency.

Associated with the seat section 15 I provide converging blade-engaging members 29 similar to the flanges 28 and engageable with the other set 26 of the beveled sides. The flanges 29 are preferably in the form of springs, as shown more clearly in Figure 4; and they engage the beveled side portions 26 in wedged relationship therebetween. The latter engagement serves not only to advance the blade toward the guard 27, but it also serves to retain the blade upon the seat in proper position. Furthermore, if the proper blade is associated with the holder, the en-

gagement referred to, i. e., between the flanges 29 and the bevels 26, will at the same time position the cutting edge 24 along the proper theoretical line with respect to the guard edge 28.

When the device is employed, the section 15 is lowered into the position of Figure 2. The proper blade is then inserted edgewise between the flanges 28. Thereupon, the handle 10 is screwed upwardly and the blade seat section 15 will gradually approach and ultimately reach the normal position of Figure 1. During this upward movement of the section 15, the resilient flanges 29 will engage the bevels 26, snapping over them and holding the blade firmly in proper position upon the composite seat.

In Figure 4, the full line representation of the blade 22 represents its relationship to the flanges 29 during the upward movement of the section 15; and the dot and dash line representation of the blade 22 represents its relationship to the flanges 29 and the seat section 15 after the latter has been brought to its normal position of Figure 1.

It will be obvious that the provision of a cutting edge 24 is optional. If the cutting edge is omitted, the blade will be technically a single-edged blade, yet the device will operate with the same efficiency and facility. Similarly, although I have shown a symmetrical blade, such symmetry is not essential, just so long as the flanges 29 are properly designed to engage with the bevels 26, and the flanges 28 are properly designed to engage with the bevels 25. Obviously, however, if the blade is symmetrical, the blade may, if desired, be reversed, so as to position the edge 24 over the guard edge 27, although such reversal is as a matter of fact unnecessary and uncalled for by the nature of the device.

It will be noted that the entire device is extremely simple, compact, and easy to employ. It embodies a number of the advantageous characteristics of the type of razor which locates the blade by holes therein while at the same time the disadvantageous characteristics accompanying the complete dependence for location upon such holes in the blade, have been obviated. Among these advantages is the adaptability of the razor to the employment of a double edged blade therein. Furthermore, the proper positioning of the blade is always secured, provided the proper blade is employed.

It will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative and not in a limiting sense.

Having thus described my invention and illustrated its use, what I claim as new and desire to secure by Letters Patent is—

1. A razor blade holder comprising a composite blade seat, said seat including two mutually pivoted parts each of which is provided with a guard edge, and a set of converging blade-engaging flanges associated with one of said parts.
2. A razor blade holder comprising a composite blade seat, said seat including two mutually pivoted parts each of which is provided with a guard edge, and a set of converging blade-engaging flanges associated with one of said parts, and means for pivoting one of said blade seat parts with respect to the other, said means comprising a lug carried by one of said parts, an adjustable handle for the blade seat and means operable upon adjustment of the handle with respect to the blade seat for cooperating with said lug to move said part.
3. In combination with a double edged wafer-type razor blade having opposite sets of beveled side edges each set converging toward the adjacent cutting edge, a razor blade holder comprising a blade seat having a guard edge, blade-engaging members associated with the seat at opposite ends of the guard edge and adapted to receive a set of said beveled side edges between them in wedged relationship to limit the positioning of the front blade edge over the guard edge, and means engaging the set of said beveled side edges toward the rear thereof for preventing retractive movement of the blade and thereby securing it in proper position.
4. In combination with a double-edged wafer-type blade having side edges beveled so as to converge toward each cutting edge, a razor blade holder comprising a blade seat having a guard edge, blade-engaging members associated with the guard edge to limit the advancement of a selected cutting edge thereover, said members cooperating with the beveled side edges adjacent to said selected cutting edge, and means carried by the blade seat and engaging the beveled side edges adjacent to the inoperative edge for advancing the selected cutting edge over the guard edge and preventing retractive movement of the blade.
5. In combination with a razor blade holder comprising a sectional blade seat, a guard edge on one section, blade-engaging members associated with said guard edge, and blade-engaging members including angularly disposed springs carried by the other section, said sections being relatively pivotal, a double-edged wafer-type blade having side edges converging toward each cutting edge, the converging edges adjacent to one cutting edge being adapted to wedge themselves between said first-named blade-engaging members, and the converging edges adjacent to

the other cutting edge being engageable by said angularly disposed springs.

6. In combination with a wafer-type razor blade having beveled side edges, a razor blade holder comprising an adjustable blade seat and including a guard edge, blade stops associated with the guard edge to limit the advancement of the front blade edge thereover, and means engaging said beveled side edges for advancing the blade and securing it in position, said means including angularly disposed springs carried by the blade seat and operable upon adjustment thereof.

7. In combination with a wafer-type razor blade having beveled side edges, a razor blade holder comprising a blade seat having a guard edge, said seat comprising a pivoted part movable into and out of the normal plane of the seat, blade stops associated with the guard edge to limit the advancement of the front blade edge thereover, and means engaging said beveled side edges for advancing the blade and securing it in position, said means including angularly disposed springs carried by said pivoted part and operable upon pivotal movement thereof into normal position.

8. A razor blade holder comprising a blade seat provided with up-standing blade engaging flanges which converge in opposite directions to form sets of oppositely converging side edges, one set being shaped to form blade side engaging channels, and means for withdrawing the other set of side edges from the plane of the seat, said means including a blade seat part carrying said other set and hinged to the rest of the blade seat to permit adjustment thereof out of the plane of the blade.

9. A razor holder comprising two members pivotally associated together end to end, along a line substantially midway of the holder to present their upper surfaces in a common plane, and together serving as a blade seat, and having means to hold a blade thereon in shaving relation thereto, a handle for the holder associated with one of the members, part of the handle being adjustable, the other member and said adjustable handle part having camming portions which cooperate upon the adjustment of said adjustable handle part to move said other member into operative position.

In witness whereof I have signed and sealed this specification.

ISAIAH N. ZELLER. 12
